CLAIM

The ornamental design for a display screen or portion thereof with a graphical user interface for a multi-chamber washer disinfector system as shown.

DESCRIPTION

FIG. 1 is a front view of a display screen or portion thereof with a graphical user interface for a multi-chamber washer disinfector system in a first sequence of an animation according a first embodiment of the claimed design; FIG. 2 is a front view of a display screen or portion thereof with a graphical user interface for a multi-chamber washer disinfector system in a second sequence of the animation of FIG. 1;

FIG. 3 is a front view of a display screen or portion thereof with a graphical user interface for a multi-chamber washer disinfector system in a third sequence of the animation of FIG. 1;

FIG. 4 is a front view of a display screen or portion thereof with a graphical user interface for a multi-chamber washer disinfector system in a fourth sequence of the animation of FIG. 1;

FIG. 5 is a front view of a display screen or portion thereof with a graphical user interface for a multi-chamber washer disinfector system in a fifth sequence of the animation of FIG. 1;

FIG. 6 is a front view of a display screen or portion thereof with a graphical user interface for a multi-chamber washer disinfector system in a first sequence of an animation according to a second embodiment of the claimed design; FIG. 7 is a front view of a display screen or portion thereof with a graphical user interface for a multi-chamber washer disinfector system in a second sequence of the animation of FIG. 6;

FIG. 8 is a front view of a display screen or portion thereof with a graphical user interface for a multi-chamber washer disinfector system in a third sequence of the animation of FIG. 6;

(Continued)

FIG. 9 is a front view of a display screen or portion thereof with a graphical user interface for a multi-chamber washer disinfector system in a fourth sequence of the animation of FIG. 6; and,

FIG. 10 is a front view of a display screen or portion thereof with a graphical user interface for a multi-chamber washer disinfector system in a fifth sequence of the animation of FIG. 6.

The appearance of the figures sequentially transitions between FIGS. 1-5 and FIGS. 6-10. The process or period in which one image transitions to another forms no part of the claimed design.

The dot-dash-dot broken lines illustrate a display screen, which is the environment of the design, and which forms no part of the claimed design. The remaining even-length broken lines, which make up portions of the graphical user interface, form no part of the claimed design.
